UNITED STATES PATENT OFFICE.

WILLIAM ESTY, OF LACONIA, NEW HAMPSHIRE.

WIDENED TUBULAR KNIT FABRIC AND THE ART OF KNITTING THE SAME.

SPECIFICATION forming part of Letters Patent No. 371,565, dated October 18, 1887.

Application filed May 5, 1887. Serial No. 237,905. (No specimens.)

To all whom it may concern:

Be it known that I, WILLIAM ESTY, of Laconia, in the county of Belknap and State of New Hampshire, have invented certain new 5 and useful Improvements in Widened Tubular Knit Fabrics and the Art of Knitting the Same, of which the following, taken in connection with the accompanying drawings, is a specification.

10 My invention relates to the manufacture of widened tubular knit fabrics; and it consists in a certain novel arrangement of loops composing the seam in that portion of the fabric where the widening takes place, and in a novel 15 art or method of knitting said widened tubular fabric, all of which will be readily understood by reference to the description of the drawings, and to the claims, to be hereinafter given.

Figure 1 of the drawings is a side elevation 20 of a shirt-sleeve, illustrative of my invention; and Fig. 2 is an enlarged elevation of a portion of the same, showing the form and arrangement of the stitches which constitute the seam in that part of the fabric where the widening takes 25 place.

In the manufacture of my improved widened tubular fabric I use an automatic machine having two sets of needles arranged in 30 rows parallel to each other upon fixed beds, said beds being so inclined to each other that the needles in either row, when moved endwise by the action of the needle-cams thereon, will cross the plane of movement of the other set of needles; a two - armed yarn - carrier constructed and arranged to feed two yarns to said needles, one to each row of needles, at the same 35 time; means for moving said carrier over said rows of needles and reversing its ends at each end of the rows of needles, so that the yarn 40 which is fed to one row of needles when the carrier is moving in one direction will be delivered to the other row of needles when it moves in the opposite direction, and a pattern-chain for automatically throwing into and out 45 of action the needles for forming the widening seam.

An example of the arrangement and operation of the yarn-carrier is presented in Letters Patent No. 302,119, granted to me July 15, 50 1884, and an illustration of the needles and the pattern-chain for throwing said needles into

and out of action is presented in another application of mine filed December 12, 1884, Serial No. 150,160, and the Letters Patent No. 247,325, granted to me September 20, 1881, in 55 which one set of needles and the pattern-chain for operating them is shown, the other set of needles and pattern chain being placed opposite those shown, with the angle of inclination of the needles and needle-bed reversed and 60 the sinker-hooks about one-sixteenth of an inch apart.

In the drawings, A and B represent portions of the fabric which are knit straight, or with a uniform number of stitches in each course of 65 each section, but with a different number of stitches in the courses of A to those in B, and C is a section located between A and B, and in which the widening to give the taper to the fabric takes place. This tapered tubular fabric 70 may be a stocking, the sleeve of a shirt, the leg of a pair of drawers, or any other tapered tubular knit fabric, and is knit by commencing at the small end and at the proper times widening to increase its diameter and give the 75 desired taper thereto.

If a shirt-sleeve is to be knit, the wrist-band D is first knit, and then a straight tubular portion, B, is knit, extending to the line a, when the widening begins. Up to this point 80 the two yarns have each been fed alternately to each set of needles, said yarns crossing each other at each end of the rows of needles, and each course knit having the same number of stitches, the number of needles in action being 85 the same in all the courses. When the point for beginning the widening is reached and the yarn-carrier is at the right-hand end of the machine, an additional needle at the opposite end of each row of needles is thrown 90 into action, and the end needle of each row of the needles previously in action and next to the new needle thrown into action and the third needle from said new needle are thrown out of action, two courses are knit, the new needles 95 catching the yarns of the first course and drawing them to the other side; but as there are no stitches upon said new needles to draw the new loops through, said yarns are cast off as the new needles are moved forward again, and 100 said new needles catch the yarns of the last course, and when the yarn-carrier has again

reached the right-hand end of the rows of needles the needle last thrown into action is again thrown out of action, drawing down a loop of yarn below the plane of movement of the yarns 5 as they are being knit into the fabric, and the two needles which were last thrown out of action, still holding the loops of yarn held thereby when thrown out, are again thrown into action, and the loops *b b*, held by said needles, 10 are knit into the next course. Two or more courses are now knit upon the original number of needles, while the new needles, with the loops held thereby, remain out of action, and then said new needles are again thrown into 15 action, and the loops *c c*, carried thereby, are knit into the next succeeding course. This operation is repeated as often as it is desired to widen, and is continued until the point is reached where it is desired to discontinue the 20 widening, when any desired number of courses are knit upon the needles then in action without adding to or subtracting therefrom to complete the straight section A, and then the gusset E is knit by widening, as before. When 25 completed, the seam of that portion of the fabric where the widening is done will consist of a series of repetitions of the following features, viz: one or more courses in which the yarns are crossed at the seam, as at *dd*, a plurality of loops 30 *b c* drawn from a lower course upon each side of the center of the seam over said crossed yarns or first-named courses to a course above and knit into said course, one of said loops upon each side of the center of the seam being carried 35 up by a new needle being thrown into action, as heretofore described, thus increasing the number of stitches in the course and widening the fabric.

My present invention is a great improvement 40 upon the invention described in the Letters Patent No. 302,119, in that a much more tightly-closed widening seam is produced when a plurality of loops upon each side of the center of the seam are taken from courses below 45 and carried up over two or more courses and knit into a succeeding course or courses than

when only one such loop is so knit upon each side of said seam at each widening.

What I claim as new, and desire to secure by Letters Patent of the United States, is— 50

1. A widened tubular fabric having the seam in that portion where the widening is done composed of a series of repetitions of one or more courses of crossed yarns, as *dd*, and a plurality of loops upon each side of the center 55 of said seam drawn from a course below over and above said first-mentioned courses and knit into a course above at each widening, one of said loops upon each side of the seam increasing the number of stitches in said course and 60 widening the fabric.

2. The method of knitting a widened tubular fabric with two yarns on two distinct sets of needles, which consists in throwing into action a new needle at one end of each row of 65 needles, at the same time throwing the needle next to said new needle out of action, still holding the loop thereon, then knitting one or more courses with two yarns fed in opposite directions, then throwing out of action the last 70 needles thrown in, and at the same time throwing into action the needles last previously thrown out of action, knitting the loops carried by said needles into a succeeding course, then knitting one or more courses, and then 75 throwing into action the new needles previously thrown in to seize the yarn and then thrown out again, and knitting the loops carried by said new needles into a succeeding course, thus increasing the number of stitches 80 in the course and widening the fabric, and repeating said operations until the widening is completed.

In testimony whereof I have signed my name to this specification, in the presence of two 85 subscribing witnesses, on this 28th day of April, A. D. 1887.

WILLIAM ESTY.
